ATTORNEY

UNITED STATES PATENT OFFICE.

ROZE E. BENNETT, OF FORT SMITH, ARKANSAS.

HOSE SUPPORTER.

Application filed June 19, 1926. Serial No. 117,133.

This invention relates to a stocking supporter, the general object of the invention being to provide a belt with depending strips having stocking engaging means 5 thereon for supporting the stockings at two sides of each leg.

This invention also consists in certain other features of construction and in the combination and arrangement of the several 10 parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:

Figure 1 is a view showing the device in 20 use.

Figure 2 is an enlarged perspective view of the device.

In these views, 1 indicates the belt of the device which is provided with the fastening 25 means 2 at its front so that it can be fastened around the waist of the wearer. Four depending strips are fastened to each side of the belt, two of the strips 3 and 4 being fastened at the same point adjacent the rear 30 of the belt, as shown at 5, while the other two strips 6 and 7 are fastened at the same point to the belt adjacent the front thereof, as shown at 8. The strips 3 and 6 are adapted 35 to engage the outside portion of each leg and these strips have their lower ends connected together, as shown at 9, where they are connected with the upper end of the adjustable tab 10 which carries the stocking clamp 11. The strips 4 and 7 are adapted to 40 engage the inner portion of the leg and the lower ends of these strips are connected together, as at 12, and are fastened to the upper end of the clamp supporting tape 13. The strips, at the other side of the belt, are 45 similarly arranged. Thus I have provided a device which will support each stocking at the outer and inner side of each leg, so that the stocking cannot wrinkle and is prevented from turning, so that the seam at the back

of the stocking will remain straight. The strips will engage the body in such a manner that they will not cause discomfort to the wearer, and the entire weight comes on the belt.

It is thought from the foregoing description that the advantages and novel features of my invention will be readily apparent. I desire it to be understood that I may make changes in the construction and in the combination and arrangement of the several 60 parts, provided that such changes fall within the scope of the appended claims.

What I claim is:

1. A stocking supporting device comprising a body encircling member, a pair of strips connected with the member at each side thereof and adapted to engage the outer portion of each leg of the wearer, said strips having their lower ends connected together, stocking supporting means connected with the lower ends of said strips, a second pair of strips connected to each side of the member and having their lower ends connected together, the second pair of strips engaging the inner portion of each leg and stocking supporting means connected with the lower ends of said second pair of strips.

2. A stocking supporting device comprising a belt, a pair of strips connected with the belt at each side thereof and adapted to engage the outer portion of each leg of the wearer, said strips having their lower ends connected together, stocking supporting means connected with the lower ends of said strips, a second pair of strips connected to each side of the belt and having their lower ends connected together, the second pair of strips engaging the inner portion of each leg, stocking supporting means connected with the lower ends of said second pair of strips, the front strip of each pair of strips at each side of the belt being connected together at their upper ends and the rear strips of each pair of strips at each side of the body being connected together at their upper ends.

In testimony whereof I affix my signature.
ROZE E. BENNETT.
